UNITED STATES PATENT OFFICE.

HEINRICH DEGENER, OF BERLIN, GERMANY, ASSIGNOR TO MERGENTHALER LINOTYPE COMPANY, A CORPORATION OF NEW YORK.

ASSEMBLING MECHANISM OF TYPOGRAPHICAL COMPOSING-MACHINES.

1,121,899.

Specification of Letters Patent.

Patented Dec. 22, 1914.

Application filed October 3, 1911. Serial No. 652,486.

To all whom it may concern:

Be it known that I, HEINRICH DEGENER, a subject of the German Emperor, residing at 26 Hollmannstrasse, Berlin, in the German Empire, have invented new and useful Improvements in the Assembling Mechanism of Typographical Composing-Machines, of which the following is a specification.

10 The present invention consists of improvements in the assembling mechanism of typographical machines for composing mixed matter, *i. e.*, matter in more than one face, and more particularly in the mechanism described in U. S. patent to Philip T. Dodge, No. 547633, October 8th 1895, a mechanism characterized by an assembler box to receive the composed line, and having fixed rails thereon to support the matrices at different 20 heights according to face; a guide down which the matrices slide successively; means positioned before the assembler box for adjusting the matrices successively in respect of face before they reach the entrance mouth of the said box; and a star wheel to push 25 the matrices successively through the said mouth.

Referring to the accompanying drawings which are to be taken as part of this specification and read therewith, Figures 1 and 2 are sectional front elevations of one constructional form of the invention applied to an assembler box having two fixed supporting rails and show a two-face matrix being 30 assembled on the upper and lower rail respectively. Figs. 3 and 4 are similar elevations of a second constructional form applied to the same assembler box and respectively show the same assemblies.

40 1 is the assembler box; 2, its upper fixed rail; 3, its lower fixed rail; 4, the guide down which the matrices 6 slide; 7, the axle of the star wheel; each matrix being supposed to have its character in only two faces. 45 These parts are substantially as in the Patent 547633 above mentioned. The star wheel hitherto used is replaced by a rotating matrix pusher 9 as shown in Figs. 1 and 2, or 9^a as shown in Figs. 3 and 4, which is 50 shown as having two equal and radial arms, but may have any number. The radial length of an arm is such that the circle which it describes touches (as shown in Figs. 1 to 4) the plane of the entrance 55 mouth of the assembler box 1. The direc-

tion of this pusher's rotation is the same as that of the known star wheel. 10 is a recess or seating in the following edge 11 of an arm close to the tip 12 of it. It receives the foot of the matrix being assembled, as the 60 latter slides down the guide 4, (as shown in full line in Fig. 1), and, as the seating 10 moves from under the said foot, the matrix drops (as shown in dotted line in the same figure) upon the matrix support next described, whereupon the next (in the direction of rotation) leading edge 13 comes up to the said matrix, engages the latter and pushes it through the said entrance mouth. The figures show a leading edge 13 as being 70 rectilinear, and when it is so, this edge will engage over the greater portion of the length of the matrix at a greater or less angle, according as to whether this edge 13 is parallel with a diameter of the pusher 75 (Figs. 3 and 4) or at an angle therewith (Figs. 1 and 2). The parallelism of an edge 13 with a diameter of the pusher widens the respective tip 12 in an arcual sense, thereby enabling it to act as a stop 80 in the path of the next matrix sliding down the guide 4, as shown in Fig. 4, until the preceding matrix is in the assembler box 1 or the respective seating 10 is ready to receive the foot of the said next matrix. 85

The improved face adjusting means consists of a fixed surface 14 practically flush with the lower rail 3 and a horizontal slide 15 sliding upon a suitable guide such as a slot and set-screw device 16. 17 is the operative surface of this guide, and each of these surfaces 14 and 17 acts as a support for the matrix as soon as it has dropped from the pusher 9. The vertical distance separating the two surfaces 14 and 17 is equal to that 90 which separates the two faces on a matrix, center to center. Only one slide 15 with its surface 17 is shown, but there may be as many slides (and also rails 2) as there are faces on a matrix beyond unity. It is to be 95 noted that the slide 15 is not an automatic one worked by any member of either the assembling mechanism or the composing mechanism of the machine, but is a manual one to be worked by a special act of the 100 operator independent of his depression of a finger key on the keyboard of the machine. It is worked as follows: If the copy calls for the top face, the slide 15, is drawn away 105 from the over the support 14. If the copy 110

calls for the bottom face the slide is pushed until its support 17 stands over the support 14.

So far the description has related to a form of mechanism to be employed in connection with matrices having two characters. In the event that matrices with more than two characters are to be employed, the number of supporting ledges in the assembler and of slides to register therewith could, of course, be correspondingly varied in the manner familiar to those skilled in the art.

Having described my invention, I declare that what I claim and desire to secure by Letters Patent is:—

1. In an assembling mechanism of the type stated for a typographical composing machine for mixed matter, the combination 20 of a rotating matrix pusher with face-adjusting means onto which the matrices are delivered by the pusher within its path of rotation, the said pusher being formed with a projecting portion and an adjacent seat to receive and temporarily retain a matrix until it is delivered to the face-adjusting means.

2. In an assembling mechanism of the type stated for a typographical composing 30 machine for mixed matter, the combination of the assembler box, a rotating matrix pusher, and face-adjusting means onto which the matrices are delivered by the pusher within its path of rotation, the said pusher being formed with a projecting portion and an adjacent seat to receive and temporarily retain a matrix until it is delivered to the face-adjusting means, and also with a leading edge to push the preceding matrix 40 into the assembler box.

3. In an assembling mechanism of the type stated for a typographical composing machine for mixed matter the combination 45 with the assembler box provided with a bottom matrix-supporting rail and a top matrix-supporting rail, of a device for adjusting the height at which each matrix shall enter the said box, consisting of a stationary support before the entrance mouth of the said box and on a level with its bottom matrix-supporting rail and a manually operated slide likewise before the said entrance mouth and on a level with the top matrix-supporting rail and adapted to either allow the matrix being assembled to drop on to the stationary support or to be moved up to the said top rail.

4. In an assembling mechanism of the type stated for a typographical composing 60 machine for mixed matter, the combination with the assembler box provided with a bottom matrix-supporting rail and a top matrix-supporting rail, of a device for adjusting the height at which each matrix shall 65 enter the said box, consisting of a station-

ary support before the entrance mouth of the said box and on a level with its bottom supporting rail and a slide likewise before the said entrance mouth and on a level respectively with the upper matrix-supporting rails and adapted to allow the matrix being assembled to drop on to the stationary support or to be moved up to the respective upper matrix-supporting rail.

5. In a typographical composing machine, 75 the combination of the assembler provided with means to receive and support the matrices at upper and lower levels, with an independent exterior device to guide the matrices thereto at the upper level, and movable horizontally away from the assembler to permit the matrices to pass thereby to the lower level.

6. In a typographical composing machine, 85 the combination of the assembler provided with means to receive and support the matrices at upper and lower levels, with an exterior guiding device to register with the upper supporting means and movable horizontally toward and from the assembler so as to effect the delivery of the matrices thereto at the upper or lower level as desired.

7. In a typographical composing machine comprising assembling mechanism, the combination 95 of the assembler provided with means to receive and support the matrices at upper and lower levels, with an independent horizontally movable exterior guiding device to register with the upper supporting means, and a stationary element to register with the lower supporting means, whereby the adjustment of the guiding device effects the delivery of the matrices at the upper or lower level as desired. 105

8. In a typographical machine, the combination with the assembler, of a support having an elongated surface upon which the matrices may rest temporarily outside of the assembler, and a rotating device of 110 such form as to push the individual matrices off the support into the assembler.

9. In a typographical machine, the combination with the assembler, of a support having an elongated surface upon which the 115 matrices may rest temporarily outside of the assembler, and a rotating device to engage the matrices while on the support and having its path of rotation extending to or beyond the extremity of the support so as 120 to push the matrices therefrom into the assembler.

10. In a typographical machine, the combination with the assembler, of a support having an elongated surface upon which the 125 matrices may rest temporarily outside of the assembler, and a rotating device of such form as to push the matrices off the support into the assembler, said device being formed to prevent the delivery of a second matrix 130

to the support until the first matrix has been pushed therefrom.

11. In a typographical machine, the combination with the assembler, means for supporting the matrices temporarily outside of the assembler, and a rotating device to deliver the matrices to the outside supporting means, the said device comprising radial arms, each formed with a recess to receive and temporarily hold a matrix until it is delivered to the supporting means.

12. In a typographical machine, the combination with the assembler, of a support having an elongated surface upon which the matrices may rest temporarily outside of the assembler, and a rotating device to engage the matrices while on the support and comprising a plurality of radial arms, each of such length as to adapt it to push the matrices from the support into the assembler.

13. In a typographical machine, the combination with the assembler, of a support having an elongated surface upon which the

matrices may rest temporarily outside of the assembler, and a rotating device to engage the matrices while on the support and comprising a plurality of radial arms, each adapted to push the matrices from the support into the assembler, and acting during its pushing movement to arrest a second matrix and prevent its delivery to the support.

14. In a typographical machine, the combination of a rotating matrix pusher, and means to support the matrix temporarily in the path of rotation of the pusher, the said pusher comprising a plurality of radial arms, each formed with a recess to receive and hold a falling matrix and deliver it to the supporting means.

In witness whereof I have hereunto set my hand in the presence of two witnesses.

HEINRICH DEGENER.
